WILLIAM THOMAS SNOWDEN, OF TORONTO, OHIO.

COMBUSTION-FACILITATING DEVICE FOR INTERNAL-COMBUSTION ENGINES.

1,238,450.

Specification of Letters Patent. Patented Aug. 28, 1917.

Application filed September 12, 1916. Serial No. 119,607.

To all whom it may concern:

Be it known that I, WILLIAM THOMAS SNOWDEN, a citizen of the United States of America, and resident of Toronto, county 5 of Jefferson, and State of Ohio, have invented certain new and useful Improvements in Combustion-Facilitating Devices for Internal-Combustion Engines, of which the following is a specification.

10 This invention relates broadly to fuel economizers for internal combustion engines, and more particularly to an apparatus for facilitating the combustion of gases in such engines.

15 The primary object of the invention is to provide an apparatus whereby an emulsion or mixture of mineral oil and water may be controllably supplied to the manifold of an internal combustion engine for 20 mixing with the vaporized fuel which is drawn through said manifold in the usual manner to produce explosive charges which are more readily combustible and which, consequently, possess materially increased 25 potential energy.

A further object is to provide an apparatus of the character mentioned designed for the introduction in an engine of a combustion-facilitating fluid or mixture of 30 fluids for preventing the deposit of carbon in the engine cylinders.

Another object within the contemplation of the invention is to provide an apparatus of the character mentioned provided with 35 controllable means whereby a supply of heated air is introduced into the manifold with the combustion-facilitating fluid, and whereby, upon throttling said fluid, the heat supply is automatically cut off and a passage 40 for the introduction of cold air for cooling the cylinders is automatically opened.

With these and other objects in view, the invention resides in the features of construction, arrangement of parts and combinations 45 of elements which will hereinafter be fully described, reference being had to the accompanying drawings, in which—

Figure 1 is a perspective view of the invention;

50 Fig. 2 is a vertical section of the casing and associated parts; and

Fig. 3 is a view of said casing in horizontal section.

Referring to said drawings, in which like designating characters distinguish like parts throughout the several views—

1 indicates a cylindrical casing having a threaded tubular stem 2 adapted for seating on the intake manifold 3 of an internal combustion engine. Removably mounted upon the top of said casing is a cover or cap 4 which has adjustably mounted therein a centrally disposed vertical tube 5 the lower end of which is shaped to form a spray nozzle 6 which approaches the upper end of the passage through the stem 2. Leading into said tube 5 at oppositely disposed points above the casing are two pipes 7 and 8, of which the former is an oil supply pipe leading from a small oil reservoir 9, 70 and the latter is a water supply pipe leading from a small water reservoir 10.

A pin 11 with a needle point constitutes a valve 1 is disposed within the tube 5 and which is adapted for adjustment with respect to the nozzle passage for controlling the passage of the mixed oil and water delivered to said tube through said pipes 7 and 8. Said pin has a fixed head 12 which is provided on its under side with a cam face, as indicated at 13; and rotatable on said pin in underlying relation to said head

is a collar 14 whose upper face corresponds to that of the engaging face 13 of the pin head 12. Said collar 14 is seated upon the upper end of an adjusting nut or sleeve 15 which loosely embraces the pin 11 and is threaded upon the upper end of the tube 5. A coil compression spring 16 disposed in encircling relation to said pin has its lower end seated upon a fixed collar 17 carried by said pin and its upper end seated against the pin-embracing portion of said adjusting nut 15, the same being designed to maintain the pin depressed with its head in yielding close-seating relation to the collar 14 and also to maintain the latter seated upon said adjusting nut. Movement 85 of the pin to and from closing relation to the nozzle 6 is accomplished in a manner which 90 will hereinafter be explained.

Disposed within the casing 1 is a close-

fitting rotary valve 18 of hollow cylinder shape which is adapted for rotary movement with respect to the latter. Rigidly attached to said valve is an arm 19 which projects outward through a horizontal slot 20 of appropriate length provided in the cylindrical wall of the casing. Said arm has pivotally connected thereto one end of an operating lever 21 whereby rotary movement may be imparted to said valve.

Provided in the valve 18 is a port 22 which is adapted to be carried into and out of register with the passage 23 of a horizontally disposed tubular stem 24 carried by the 15 casing 1, said stem having connected thereto one end of a flexible tube 25 leading from a suitable heated air source, as a radiation box or casing on the exhaust manifold (not shown). The collar 14 and arm 19 are 20 rigidly connected by means of an angular member 26, so that both will be actuated together, or simultaneously. Thus, movement designed to shut off the fluid supply through the nozzle 6 also cuts off the heated 25 air supply, and vice versa.

Also provided in the valve 18 at a suitable point is a port 27 designed to be brought into register with a passage 28 provided in the casing 1 for the admission of cold air, 30 said port 27 and passage 28 being so located relatively with respect to the aforementioned port 22 and passage 23 that the former can be placed in register only when the latter are out of register, and vice versa, 35 or when the passage of fluids through the nozzle 6 is cut off.

As is obvious, the admission of heated air is designed to facilitate the gasification of the spray of oil and water as the mixture 40 joins with the fuel mixture entering the manifold from the carburetor (not shown). It is further apparent that when cold air is admitted to the manifold, as described, for mixing with the fuel mixture entering from 45 the carburetor, the mixture furnished to the engine cylinders is rendered less efficient, resulting in a slowing down of the engine speed and a consequent braking of the speed of the vehicle which is propelled by the engine--a result which is particularly desirable, as when the vehicle is coasting down hill. Further, the admission of the cold air 50 results in a desirable cooling of the engine cylinders.

55 In practice, the nut or sleeve 15 is adjusted to regulate the relative positions of the valves 11 and 18, after which a lock nut 29 is threaded up thereagainst, as shown in Fig. 2. Stop cocks 30 and 31 provided, respectively, in the oil and water lines 7 and 8 are opened to admit the fluids to the tube 5. The passage of said fluids through the nozzle 6 is then controlled by shifting movement of the lever 21, which, as hereinbefore

explained, simultaneously controls the admission of heated air.

What is claimed is:—

1. In a device of the character described, a casing in open communication with the intake manifold of an internal combustion engine, a valve for controlling the admission of fuel to said casing, valve-controlled means for introducing heated air to said casing, and means for opening and closing said fuel and hot-air valves, said casing having a passage through which cold air is admitted thereto, said passage being opened simultaneously with the closing of said fuel and hot-air valves, and vice versa. 75

2. In a device of the character described, a casing in open communication with the intake manifold of an internal combustion engine, said casing having hot-air and cold-air inlet ports therein, a rotary valve controlling said ports and adapted to maintain 80 one thereof closed when the other is open, and vice versa, and a valve for controlling the admission of fuel to said casing and operable to and from closing position with the closing and opening, respectively, of 85 said hot-air inlet port.

3. In a device of the character described, a casing in open communication with the intake manifold of an internal combustion engine, said casing having hot-air and cold-air inlet ports therein, a rotary valve controlling said ports whereby concurrent opening thereof is prevented, a nozzle through which fuel is introduced to said casing, a valve for controlling the passage through 90 said nozzle, and means connecting said valves whereby said fuel control valve is opened and closed simultaneously with the opening and closing, respectively, of said hot-air inlet, said cold-air inlet being opened 95 simultaneously with the closing of the hot-air and fuel valves. 100

4. In a device of the character described, a casing in open communication with the intake manifold of an internal combustion engine, said casing having hot-air and cold-air inlet ports therein, a tube depending within said casing and having a nozzle, a valve adapted for adjustment into and out of 105 closing relation to said nozzle, means for introducing fuel to said tube, and means for simultaneously opening and closing said fuel valve and said hot-air inlet port, the last-mentioned means accomplishing the opening of said cold-air inlet port simultaneously with the closing of the hot-air and fuel valves, and vice versa. 115

5. In a device of the character described, a casing in open communication with the intake manifold of an internal combustion engine, a tube depending within said casing and having a nozzle, a spring-pressed pin disposed within said tube and adapted for 120

110

125

adjustment into and out of closing relation to said nozzle, means for introducing fuel to said tube, said casing having separated cold-air and hot-air inlets leading through its walls, a hollow rotary valve mounted within said casing, ports in said valve adapted for movement into and out of register with said inlets, means for rotating said valve, and means intermediate said valve and said pin whereby when the former

is rotated to a position closing the hot-air inlet the latter is seated and the opening of the cold-air inlet is simultaneously accomplished, and vice versa.

In testimony whereof, I affix my signature 15
in presence of two subscribing witnesses.

WILLIAM THOMAS SNOWDEN.
